ELECTRICAL TOY DISPLAY UNIT OR SIMILAR ARTICLE

Max Tucker, Flushing, N. Y., assignor of one-half to
Richard B. Sloane, Forest Hills, N. Y.

Application October 14, 1954, Serial No. 32,668

Term of patent 7 years

(Cl. D25—1)

FIG.1

FIG.2

Fig. 1 is a top plan view of an electrical toy display unit or similar article, showing my new design; and

Fig. 2 is a side elevational view thereof. The back of the article, not shown, is plain or conventional.

I claim:

The ornamental design for an electrical toy display unit or similar article, substantially as shown and described.
